UNITED STATES PATENT OFFICE.

FRANK R. MCBERTY, OF NEW ROCHELLE, NEW YORK, ASSIGNOR TO WESTERN ELECTRIC COMPANY, OF NEW YORK, N. Y., A CORPORATION OF ILLINOIS.

TELEPHONE-EXCHANGE SYSTEM

1,159,595.

Specification of Letters Patent.

Patented Nov. 9, 1915.

Application filed July 27, 1910. Serial No. 574,089.

To all whom it may concern:

Be it known that I, FRANK R. MCBERTY, citizen of the United States, residing at New Rochelle, in the county of Westchester and State of New York, have invented a certain new and useful Improvement in Telephone-Exchange Systems, of which the following is in full, clear, concise, and exact description.

10 This invention relates to telephone exchange systems and its objects are in general to provide improved means for the control of various switching and signaling devices thereof, whereby the answering of subscribers' calls and the interconnection and disconnection of subscribers' lines may be effected with rapidity and in an orderly and efficient manner.

15 The invention is applicable in some respects to various types of telephone exchange systems including those in which the interconnection of lines is effected wholly by manually operated switches and those also in which it is effected wholly by mechanically operated switches under the control of sending apparatus at the substations of subscribers' lines. More especially, however, the invention is applicable to semi-automatic systems wherein the sending apparatus is 20 located at the central office and arranged for manipulation by an operator in accordance with instructions given by a calling subscriber. In such semi-automatic systems the initial connections to calling lines may be 25 made by any suitable switch mechanism such as an automatic switch or an ordinary plug and jack switch, while the connections to the lines wanted are made, in part at least, by mechanical selector switches under the 30 control of the sending apparatus. The system herein described is one in which the initial connection is made by a plug and jack switch to extend the circuit of a calling line to a cord circuit which terminates in an automatic selector switch, the sending mechanism being temporarily associated with the cord circuit for the purpose of controlling the operation of said selector switch to secure 35 the connection desired.

40 One feature of the invention has for its object to provide an improved switching system which may be controlled with great flexibility to connect an operator's telephone set with the connecting circuits of a telephone exchange system. The system de-

pends primarily on the use of sequence switch mechanisms, associated with the operator's equipment, preferably one for each connecting circuit, these mechanisms being controlled, to enable the operator to listen in 45 on the circuits at will, by means of keys or other switch contacts, which may be actuated for the purpose either manually, that is, in the performance of a special act by the operator, or automatically, that is, in the 50 performance of some other act or movement of the apparatus occurring in the ordinary progress of switching other circuits.

55 The preferred arrangement is one in which a listening sequence switch mechanism or key is placed under the control of a line connecting switch, being operated automatically to connect the operator's telephone in circuit when a calling line is extended to the connecting circuit so that the operator 60 may answer the subscriber's call instantly upon the establishment of this initial connection, and being again operated automatically to disconnect the operator's telephone from the circuit when connection is made 65 initially to the line of any other calling subscriber. The line connecting switch is preferably a plug and jack, the plug forming the terminal of the connecting circuit and the 70 jack the terminal of the line calling. In the system herein described the sequence switch mechanism is caused to operate in the first instance under the control of a relay in a local circuit closed in contacts of the plug 75 and jack. It is arranged to come at rest in three positions: first, the "normal" position, in which the operator's telephone is not connected in circuit; next, the "listening" 80 position, in which the operator's telephone is connected in circuit, the movement to this position from normal occurring upon the insertion of the plug in the spring-jack of a line calling; and finally the "off listening" 85 position, in which the operator's telephone is disconnected, the sequence switch being arranged to move to off listening position upon the insertion of another plug in a 90 springjack of another line.

95 The sequence switch may if desired thereafter be caused to move automatically from off listening position to normal upon the removal of the plug from the springjack of the first mentioned calling line. A master listening-out key may be likewise provided 100 by which any switch may be caused to move 105 110

out of listening position without the insertion of another plug. And contacts may be provided on each listening switch whereby in the listening position the said switch is thus placed temporarily under the control of the listening switches of other connecting circuits; and other contacts may be provided on each listening switch whereby in passing from normal to listening position a circuit is closed to a controlling or motor magnet of any other listening switch that may be in listening position. Individual keys are preferably provided, one for each connecting circuit, by means of which the operator may cause any listening switch to advance from off-listening position to listening position again, and in such advance movement the listening switch of any other connecting circuits will be caused, in the manner already stated, to pass out of listening position to the off-listening position.

Another feature of the invention relates to means for controlling the operation of the automatic switch mechanism or selectors to cause their return movement after being operated for the interconnection of subscribers' lines. Means is provided under the control of the calling line connecting switch whereby under certain conditions the opening of that switch to disconnect the calling line will automatically cause the return movement of the selector mechanism. This control, however, is checked by the listening switch when in listening position, the arrangement being such that if the listening switch is in listening position, the calling line may be disconnected without effecting the return movement of the selector. A circuit is also provided for the control of the selector, which circuit includes contacts of the cord relay and the listening switch, whereby if the plug is withdrawn when the listening switch is in off-listening position, said circuit will become closed and the selector switch with its controlling apparatus will be caused to return to normal. A self-locking relay is provided for controlling the movement of the selector mechanism to normal. The arrangement is such that the relay may be energized under the control of a master wipe out key during a period in which the selecting operations are not completed; and when once energized, this relay will remain energized in its locking circuit to insure the complete restoration of the switch mechanism. The movement of the selector mechanism may thus be checked before it has completed the desired connection and be caused immediately to return to normal, the operator, in case she has made a mistake in the manipulation of the sending apparatus, being enabled thereby to start a new connection immediately.

A further feature of the invention relates to the control of supervisory signals, where-

by these signals are operated in a particular manner to indicate not only the condition of the connected lines, but also the condition of the switching mechanism. The signals may be ordinary electric lamps controlled in local circuits. Two supervisory signals, one for each of two connected lines and a third or ringing signal for the called line are provided. The supervisory signal for the called line is first brought into circuit under the control of a sequence switch to indicate that the operation of the selector mechanisms is incomplete, this signal being switched out of circuit upon connection being completed with the called line. It is thereafter placed under the control of a relay or other electro-responsive device controlled by current flow in the called line. The supervisory signal for the calling line is arranged not only to indicate the condition of the calling line when connection is made thereto, but also to indicate the condition of the automatic switch mechanism when connection with the calling line is broken. The signal remains visible after the plug is withdrawn to disconnect the calling line and until the automatic switch mechanism is restored to normal condition.

For the purpose of illustrating these and other features of the invention there is shown in the drawings accompanying this application the circuits and apparatus which are directly associated with a single selector and a cord connecting circuit of which the selector forms the terminal, and also those parts of the circuits and apparatus of a sender mechanism and of other selector switch mechanisms which are in some manner involved in the control of the first mentioned selector and cord circuit. This selector is only one of several which in a complete system for a very large exchange would be arranged to be operated successively in the establishment of a connection between telephone lines.

The system herein disclosed embodies a number of inventions other than the one claimed. Some of these are made the subject matter of certain other applications for patent by me, as follows: Serial Nos. 573,516, filed July 23, 1910, and 528,293, filed November 16, 1909.

In the drawings, Figure 1 shows the circuits and apparatus which are directly associated with a cord connecting circuit terminating in a selector switch mechanism, this being the "district" switch of a large telephone exchange system; Fig. 2 shows the circuits and apparatus associated with a listening switch, said switch serving to control the connection of an operator's telephone set to the connecting circuit of Fig. 1; Fig. 3 shows the circuits and apparatus associated with a sender or controlling mechanism and a cord finder, the sender

serving to control the operation of the selector switch mechanism of Fig. 1, and the cord finder to establish temporary connection between said sender and the apparatus 5 of said selector switch mechanism. Fig. 4 shows the circuit of a trunk line leading to a called telephone line to which connection may be made by the selector switch mechanism of Fig. 1. Figs. 1 to 4 inclusive may 10 be arranged to form a single circuit diagram by placing Fig. 2 above, Fig. 3 below and Fig. 4 to the right of Fig. 1. Fig. 5 shows in skeleton form a plurality of connecting circuits of one operator's position 15 and a plurality of subscribers' lines to make clear the arrangement of listening switch contacts, whereby the connections of an operator's telephone set are established and broken in the use of the connecting circuits. 20 Figs. 6, 7, 8 and 9 show in detail the structure of one of the sequence switch mechanisms by which the circuits of the selector switch and other apparatus in the system are partly controlled. Figs. 6 and 7 are 25 front and side elevations, respectively, of the sequence switch, while Fig. 8 is a view in cross section on line 8-8 of Fig. 7, and Fig. 9 is a view in cross section on line 9-9 of Fig. 7.

30 Referring to the selector mechanism as shown in Fig. 1, the switch carriage or brush carrying member thereof is of the rotary type, the frame 21 of which is mounted upon a central standard or shaft 22. At 35 the outer end of the frame a number of sets of contact brushes 23, 24, 25 are pivotally mounted upon but insulated from a rod 26, and from each other, in position to sweep over sets of line terminals 27, 28, 29. 40 The brushes have inwardly extending arms 30, bearing against which, one for each brush, are springs 31. Latches 32, one for each set of three brushes, are pivotally mounted upon a rod 33 and arranged normally to hold the brushes from being rocked outwardly into line with the stationary terminals. Bearing against the inner ends of the latches are springs 34 which hold the latches firmly against a stop rod 36. This 45 stop rod 36 serves to prevent the latches from being moved forward too far after the brushes have been released. A stop bar 35 serves to limit the outward movement of the brushes when the latches are withdrawn. 50 The latches 32 and stop bar 35 are of insulating material so that the circuits connected with the brushes will not be crossed thereby. The springs 31 make electrical connection with the brushes; they are of sheet metal 55 and form the teeth of combs which connect corresponding brushes in the several sets in multiple. Suitable wire clip terminals 37, 38 and 39 are provided for the circuit connections to the springs and brushes. 60

65 As the brush carriage is rotated to cause

the brushes to sweep over the fixed terminals, the latches first pass by a tripping device or brush selector, by which any desired set of brushes may be released and caused to swing outwardly. This tripping device 70 comprises a shaft 40 provided with radially extending fingers 41 arranged spirally about the surface of the shaft. This shaft is adapted by mechanism, to be presently described, to be rotated so as to bring the 75 fingers one after another into the line of travel of the several latches on the brush carriage. Only one set of brushes is intended to be released in a given operation.

The shaft is first rotated to bring a particular finger into position to engage the latch in the same level therewith and then the brush carriage is rotated. In passing, the outward edge of this latch strikes the end of the finger, allowing one set of three 80 brushes to be released. Continued movement of the brush carriage brings the selected set of brushes into engagement with the rows of stationary terminals in the same level therewith, these brushes trailing over the terminals and making contact therewith 85 in passing. The brush carriage is finally caused to stop with the selected brushes in contact with some one set of stationary terminals. The other brushes, not being released, are held out of contact with the terminals over which they pass. A further movement of the brush carriage in the same direction of rotation will carry the brushes over a restoring roller 69, which may be 90 pivoted to the frame and which engages the free ends of the released set, causing them to be pushed back into their normal latched position. After making a full revolution, the brush carriage is brought to rest in its 95 normal position again.

100 In the normal position of the brush carriage, as shown in Fig. 1, a pair of levers 42, 43 engage at their free ends a normal stop plate 46. At the end of lever 42 is a roller 71 which lies in a recess of plate 46, and at the end of lever 43 is a right angle extension arm 72 which makes electrical contact with said plate 46. A coil spring 105 54, acting upon an inwardly extending arm 44, serves to press the roller 71 with considerable force against plate 46 and thereby holds the brush carriage securely in its normal position. A flat spring 52 engages an inwardly extending arm 45 of the lever 43 110 and serves to press this lever outwardly but with less force than that of the coil spring 54. The spring 52 also makes electrical contact with lever 43; it is secured to but insulated from the shaft 22 of the brush carriage and terminates in a wire clip 53.

115 As the brush carriage is moved to carry the brushes over the stationary terminals, the roller 71 and the extension arm 72 engage 120 the teeth of a cam plate 50. The roller 71 125 and the extension arm 72 engage the teeth of a cam plate 50. The roller 71 130

rides over the teeth while the brushes are passing between terminals and drops into a notch as any released set of brushes is centrally located in direct contact with a set of terminals. The extension arm 72 follows behind the roller one tooth or notch and likewise engages a tooth as the brushes are passing between successive terminals. It passes through the space between teeth, however, without touching the plate 50, as the released set of brushes is centrally located in contact with the terminals. The stop bar 35 engages the inwardly extending arm 45 just as it does the arms 30 of the brushes and thus prevents the extension arm 72 of the lever 43 from touching the bottom of the notches between the teeth of plate 50, but permitting said arm 72 to touch and make contact with the top of the teeth. The teeth and notches of plate 50 are so spaced and arranged with respect to the contact lever 43 that the extension arm 72 will not break contact with a tooth of plate 50 until after the brushes make contact with the stationary terminals and the roller 71 is ready to drop into a notch. The circuit arrangement, as will presently appear, is such that the motive power for driving the brush carriage cannot be cut off until the contact is thus broken between lever 43 and plate 50 and therefore not until the brushes are in position to make good contact with the stationary terminals.

The brush selector is also provided with an interrupter or make and break contact device comprising an arm 56 pivoted to the frame at 57, engaging at its free end a toothed wheel or cam 58 which rotates with the shaft 40. This arm 56 is adapted in the rotation of the shaft to engage two contacts 59 and 60. These contacts may be springs, the free ends only of which are shown in the drawing. In its normal position the free end of the arm 56 lies in a notch of the cam 58 which is deep enough to insure an open connection with contact 59. When the shaft is away from its normal position, however, connection is made continuously with contact 59. The connection with contact 60 is intermittent, this contact being made when the arm 56 is lifted by each tooth of the cam. There are as many teeth on the cam as there are fingers 41 on the shaft 40 and therefore as many as there are sets of brushes.

The motor mechanism for causing rotation of the brush carriage comprises an annular iron friction disk 61 flexibly mounted at the lower end of the shaft 22, an electromagnet 62 which may be fixed in any suitable manner to the frame, and a constantly rotating shaft 63 carrying an iron driving roller 64. The disk 61, roller 64 and that part of the shaft 63 which extends through the center of the electromagnet 62 form the magnetic circuit of the electromagnet 62. When

therefore current is passed through the winding of the magnet, the roller 64 attracts the disk 61 and causes the latter to rotate by frictional contact therewith. A holding electromagnet 65 having a pole piece 66 extending upwardly beneath the disk 61 is adapted when current is passed through its winding to engage the disk and hold it from movement. The power shaft 63 is extended as shown in the drawing to carry a flexibly mounted driving disk 70, which is adapted to engage a roller 67 carried by the spindle 40. An electromagnet 68 controls the engagement of disk 70 and roller 67 in the same manner that the electromagnet 62 controls the engagement of disk 61 and roller 64. These devices are in fact electromagnetic clutches, one to cause movement of the brush carriage and the other to cause movement of the brush selector.

The complete selector switch mechanism is not shown in the drawing, but the elements thereof appear in their proper relation to one another so as to make clear the manner in which the mechanism operates to interconnect lines. There may be as many sets of brushes and stationary terminals as desired. For example, the switch mechanism may, as a whole, have ten sets of three brushes each and two hundred sets of fixed terminals arranged in ten levels of twenty sets each. For simplicity in the diagram there are shown only two sets of brushes, the eighth and ninth counting from the top down, and six sets of stationary terminals in two levels corresponding to the two sets of brushes shown.

Some of the circuits of the selector switch and connecting circuit of Fig. 1 are controlled by a sequence switch 105 of the circuits of the listening switch of Fig. 2, the cord finder of Fig. 3, the selector of Fig. 3, and the trunk line of Fig. 4 may be controlled by sequence switches. In general the function of the sequence switch 105 is to establish in a definite order at successive stages of the operation the various circuits required to bring into service various devices or parts in proper sequence. The sequence switch consists in its elements of a movable switch operating member, a number of circuit changers actuated in sequence as said member is moved from one position to another, an electromagnet, and motor mechanism operated or controlled by said magnet for advancing said movable member. In each position to which a movable member of the sequence switch is advanced, a circuit or set of circuits is established by which a given operation of the device under control is made possible, and at the same time another circuit is placed in a condition whereby the motor magnet of the sequence switch may be subsequently actuated so that the sequence switch will then be automatically 130

advanced to the next position, until a new set of circuits is established, bringing about a new operation or electrical condition of the device or devices under control, and so on.

5 In the form of sequence switch shown in
 Figs. 6 to 9 inclusive, the movable member is
 a vertical rotary shaft 76 carrying a number
 of switch operating cams 77, said shaft be-
 ing arranged to be driven by power applied
 10 through the agency of an electromagnetic
 clutch. The constantly driven power shaft
 78 carries a friction driving disk 79 which is
 adapted to be drawn into engagement with a
 friction roller 80 carried upon the shaft 76,
 15 by the action of a clutch magnet 81. The
 roller 80 and the disk 79 are of iron, and
 the motor magnet 81 is adapted when ex-
 cited to magnetize said roller 80, which
 serves as a rotary pole piece for said mag-
 20 net; whereby the driving disk 79 is attracted
 into engagement with said roller, the rota-
 tion of the shaft 76 thus continuing as long
 as the motor magnet 81 remains excited.

The cams 77 carried by the rotary shaft 25 76 are arranged to operate switch springs 82, forcing said springs into engagement with outer contacts 83, or allowing them to engage their alternate inner contacts 84, according to the positions of said cams. As 30 many cams and switches may be provided as the particular apparatus to be controlled may require. Certain of the switch contacts operated in the successive positions of the movable switch element may control circuits 35 for the motor magnet 81. A special switch, such as shown in Fig. 9, is also preferably provided to control a local circuit for said motor magnet, whereby after the initial energizing circuit is broken by one or the other 40 switches the motor magnet may still be excited by current in the local circuit until the next intended stopping position of the rotary element is fully reached. As shown in Fig. 9, the cam 85 for operating the "local" 45 switch is adapted to be engaged by a cam roller 86 carried by a pivoted switch lever 87. A spring 88 is arranged to act upon said pivoted lever 87 so as to press the cam roller 86 against the edge of the cam 85. When 50 the roller 86 rides upon a tooth or high part of the cam 85, said lever 87 closes a contact 89 which controls the local circuit for the motor magnet. The teeth of the cam 85 have inclined edges, so that the cam roller 55 86, after riding over the point of a tooth, is forced down the opposite slope by the action of the spring 88, and this tends to push against the cam to continue the rotation thereof until the roller 86 reaches the bottom 60 of the following notch. The rotary element is thus brought to rest accurately in each of the positions where it is intended to stop. In the operation of the device, the circuit 65 will first be closed for the motor magnet through one of the springs 82, and one or

the other of the contact anvils 83 or 84 of such spring. Then, as the motor magnet is excited and the shaft of the sequence switch begins to rotate, the contact through which the motor magnet was initially excited may be broken, but the local circuit will be maintained for the motor magnet through the contact 89 closed by the cam 85, and the rotary element will thus continue to advance until the cam roller 86 reaches the bottom of the next notch of the cam 85.

In Figs. 1 to 5, the switch springs of the sequence switches are not shown in their actual arrangement, but are so located as to give a clear arrangement of the circuits; and the operating cams are not shown. In Fig. 80

the operating cams are not shown. In Fig. 1, the clutch or motor magnet 81, its driving disk 79 and roller 80 are shown together with the various sequence switch springs and contacts 101 to 131 inclusive, the motor magnet, switch springs and contacts being located in the frame 100.

cated in the drawing in their proper circuit positions without particular regard to their structural arrangement as shown in Figs. 6 to 9. The positions of the rotary elements of each sequence switch in which any of its

contacts (except contact 101) are closed, are indicated by numbers placed adjacent to such contacts; each contact being opened in all positions except those indicated by reference numbers. For example, contact 102 is closed

numbers. For example, contact 103 is closed in the fourth, fifth, seventh, seventeenth and eighteenth positions as indicated by the numbers 4, 5, 7, 17 and 18, placed adjacent thereto. In the case of the special contact 101 operated by the $\frac{1}{2}$ "W" switch, the

101 operated by cam 85, the numbers are placed on the opposite side of the switch lever from its contact anvil and indicate positions in which the contact is opened, such contact being closed continuously while the 105

rotary element of the sequence switch is in transit between the positions indicated. It will therefore be understood that the special contact 101 is closed continuously between positions 1 and 2, 2 and 3, 3 and 4, 4 and 6.

6 and 7, 7 and 8, 8 and 9, 9 and 10, 10 and 15, 15 and 17 and 17 and 1, but opened when the sequence switch is either resting in or passing by any one of these positions. There may be say eighteen positions of the se-

may be, say eighteen positions of the sequence switch, and the cams thereof will be caused to make one complete revolution in passing from normal (position 1) through the eighteen positions and back to normal again. 115

120
again. There are shown in Fig. 1 a number of other devices which enter into the control of the selector switch mechanism or are associated in some way with the cord circuit of

which the selector forms a terminal. A 125 plug 134 forms the other or answering terminal of the cord circuit. Connected in a local circuit leading to the sleeve of the plug is a cord relay 135, this relay controlling two back contacts 136 and 137 and two front 138

contacts 138 and 139. A supervisory lamp signal 140 is included in a local circuit controlled in part by a supervisory relay 141, the winding of which is included in a talking strand of the cord circuit leading to the answering plug 134.

A repeating coil 148 is interposed in the cord circuit between the plug 134 and the selector, windings 149 of this repeating coil being included with a battery 150 in that part of the circuit which leads to the plug, and windings 151 thereof being included in that part of the circuit which leads to the selector. This latter part of the cord circuit may be closed through contacts 119 and 120 of the sequence switch without including a source of current, or through contacts 118 and 121 with a battery 152. The battery 152 is shown in various parts of the circuit diagram merely to aid in tracing the circuits. A single battery is preferable, but if desired a number of batteries may be employed in different parts of the system. A line relay 153 is also included in that part of the cord circuit which leads to the selector, its winding, however, being shunted to voice currents by a condenser 154. The line relay 153 controls a back contact 155 and a front contact 156, the front contact being connected to a ringing lamp signal 157 when the sequence switch is in the 9th position, and to a supervisory lamp signal 158 when the sequence switch is in the 10th position. These lamp signals are arranged to indicate to the operator the condition of the switch hook at the called subscriber's station.

For the purpose of controlling the restoration of the selector under certain conditions, a restoring or "knock-down" relay 159 is arranged to be energized under the control of certain switching devices to be manipulated by the operator. The circuit of this relay may be closed initially over a conductor including contact 116, closed when the sequence switch is in positions 2 to 6, and when so closed the relay becomes locked in a local circuit including contact 126 closed in positions 2 to 10 and front contact 160 of said relay. When energized this knock-down relay also opens a back contact 161 leading to various other sequence switch contacts and to the armature of line relay 153, and closes front contacts 162 and 163. Contact 162 is connected to sequence switch contact 109, the switch spring of which is in circuit with the motor magnet 81 of the sequence switch. When this contact is closed, the sequence switch is caused to run by a number of positions at which it would otherwise stop, and thus be immediately returned to normal. Contact 163 is connected through a resistance 164 to the normal stop plate 46 of the selector mechanism.

The test circuit conductor for the selector includes two relays 165 and 166, the former

having two windings, 167 of high resistance and 168 of low resistance, and the latter relay having but a single winding of low resistance. In the fourth position of the sequence switch, the test conductor is closed from test brush 25 through sequence switch contact 107, high resistance winding 167 of test relay 165, winding of relay 166, sequence switch contact 105 and back contact 161 of the knock-down relay 159, and as the brush 75 carriage is moved to carry the brushes over the stationary terminals and the test brush 25 makes contact with the test terminals 29, current will flow from the battery connected to that terminal over the path just traced. 80 As will appear presently, relay 165 will respond to such current only in case connection is made to an idle line and will then close its contact 169 to bring the low resistance winding 168 into shunt of the high resistance winding 167, thereby increasing the flow of current in the test circuit and causing the energization of relay 166. This relay 166 will then open its back contact 170 and close its front contact 171. Contact 170 is connected to the motor magnet 62 of the selector brush carriage and contact 171 is connected to the motor magnet 81 of the sequence switch and also to the holding magnet 65 of the brush carriage. The function of relay 166 therefore is to control the movement of the brush carriage of the selector and to cause it to stop at any desired position. Test relay 165, by causing an increased flow of current in the test circuit, will create a condition at the test terminal of the line selected which will cause that line to test busy to other selectors. Leading from the conductor which joins relay 166 and the winding 167 of relay 165 is a branch conductor 172 which terminates in the spring 52. It will be remembered that this spring makes contact with lever 43, which in turn is caused to make intermittent contact with the teeth of the grounded cam plate 50 as the brush carriage is rotated. This branch connection therefore intermittently shunts the winding of relay 166, and the arrangement is such that the short-circuit is broken at periodic intervals which correspond to the positions in which it may be desired to cause the brush carriage to stop. That is to say, the short-circuit by way of conductor 172 is maintained while the brushes are traversing the spaces between successive stationary terminals and is not broken until after the brushes have made good contact with said terminals. Relay 165, however, is continuously in circuit and responds the instant the test brush 25 makes contact with the test terminal 29 of an idle line. A moment later, when the brushes become centrally located in contact with the terminals, the short-circuit is interrupted and relay 166 responds, thereby 110 opening the circuit of the motor magnet 62 115 120 125 130

and closing the circuit of the holding magnet 65 in the manner before stated.

Referring to Fig. 2 which shows the operator's listening set and switches associated therewith, it will be noted that the circuits are controlled by a sequence switch and a number of manually operable keys. The sequence switch is represented, in the same manner as the one in Fig. 1, by a motor magnet 281, a driving disk 279, a roller 280 and contacts 201 to 214 inclusive, contact 201 being the special contact corresponding in function to contact 101 of the sequence switch of Fig. 1. Contacts 209 and 212 are closed in all positions except the fifth and are interposed serially in the two strands of that part of the cord circuit which leads to the answering plug 134. In the fifth position, contacts 209 and 212 are opened and contacts 210 and 211 are closed. Contacts 213 and 214 are also closed in the fifth position so that the cord circuit is then completed by way of said contacts 210, 211, 213 and 214 and the normal contacts 228 of a ringing key 229. The contact spring for controlling sequence switch contacts 209 to 212 inclusive is of somewhat different construction from the other switch springs of the sequence switch. That is to say, these springs are so constructed that the opposing contacts are made and broken without interrupting the circuit. When the sequence switch is moving into the fifth position, contacts 210 and 211 will be made before contacts 209 and 212 are broken, and likewise when the sequence switch is moving into the sixth position contacts 209 and 212 will be made before contacts 210 and 211 are broken. The ringing key 229 is adapted, when the sequence switch is in the fifth position, to "ring back" the calling subscriber by opening the cord circuit to the repeating coil windings 149 and connecting a ringing generator 217 through the normally open contacts 230 in circuit with the calling line.

The operator's telephone set may comprise a receiver 218, condenser 219, induction coil 220 and transmitter 221, the latter being in a local circuit with the primary winding of said induction coil 220 and a battery 222. The operator's telephone set and the ringing key 229 may be common to an operator's position, while the ringing generator 217 may be common to the exchange or to one of the offices thereof.

In addition to the contacts controlled by the sequence switch, the operator's keyboard equipment comprises an individual listening-in key 223, one for each cord circuit, a master listening-out key 224, a master wipe-out key 225 and a master flash back key 226, the master keys being common to an operator's position. The functions of these keys will be stated in the description of the operation of the system. The sequence switch

spring which controls opposing contacts 202 and 203 is connected by a conductor 227 to the corresponding springs of other listening keys of an operator's position. Three such sequence switch springs are shown in Fig. 2. 70

A plurality of cord circuits and their listening switches are represented in Fig. 5 to show the manner in which the use of one may affect the connections of another. In this figure there are also shown a plurality 75 of subscribers' lines, one of which is represented as extending from a substation 501 over line conductors 502 to a springjack 503 and to terminals 504 and 505 of automatic selector switches. The sleeve of the springjack is connected through a cut-off relay 506 to the free pole of battery 152. The line circuit is normally closed through a line relay 507 and contacts of said cut-off relay, this line relay controlling a line signal 508 in a 80 local circuit. The arrangement is one which is commonly employed in telephone exchange systems.

In addition to the answering plug 134, cord relay 135, the listening key sequence 90 switch clutch magnet 281, and contacts 201, 202, 203, 206 and 216 thereof which appear in Figs. 1 and 2, also there are shown in Fig. 5, answering plugs 234 and 244 together with cord relays 235 and 245, magnets 286 95 and 291 and sequence switch contacts 241, 242, 243, 246, 256 and 261, 262, 263, 266 and 276. Two subscribers' lines 512 and 522, other than line 502, with their springjacks 513 and 523 and cut-off relays 516 and 526 100 are also indicated in Fig. 5. It may be assumed that any one of the three answering plugs may be inserted by an operator in any one of the spring jacks.

The circuits of the cord finder as shown in 105 Fig. 3 are controlled by a sequence switch comprising motor magnet 379, driving disk 381, roller 380 and contacts 301 to 308 inclusive, while the circuits of the sender or controlling apparatus are governed by a sequence switch comprising motor magnet 391, 110 driving disk 389, roller 390 and sequence switch contacts 351 and 361 inclusive.

The mechanism of the cord finder comprises five brushes 309 to 313 inclusive and 115 as many sets of five stationary terminals 314 to 318 inclusive as there are cord connecting circuits in an operator's position, eight sets being shown. The brushes are mounted on a carriage adapted to rotate with a shaft 120 319, at the lower end of which is a flexibly mounted disk 320. This disk is adapted to be engaged by a roller 321 mounted on a continuously moving power shaft 322, the engagement being under the control of a 125 motor magnet 323. The disk 320 is also adapted to be engaged by a holding magnet 324. The mode of control of the brush carriage by the magnets 323 and 324 is substantially the same as that of the selector brush 130

carriage of Fig. 1, and a test relay 325 having a back contact 326 and a front contact 327 controls the circuits of said magnets in a manner similar to the control by relay 166 of motor magnet 62 and holding magnet 65 of the selector shown in Fig. 1.

The sender or controlling apparatus, shown below and to the left of the cord finder in Fig. 3, comprises two series or 10 strings of counting relays 331 to 338 inclusive and 341 to 348 inclusive, a stepping relay 362, a cut-off relay 363 and a relay 364 for controlling the operation of the sequence switch. In addition to these relays, the 15 circuit at the sender includes a reset relay 365. The function of the stepping relay 362 is to cause the successive operation of the counting relays. As will presently appear, this stepping relay is intermittently energized to 20 alternately close its front contact 366 and its back contact 367. Relays 331 to 338 inclusive may be considered as the main counting relays, and relays 341 to 348 as auxiliary thereto. Upon the first energization of 25 stepping relay 362, a circuit is closed for the first auxiliary counting relay 341 from battery 152, sequence switch contact 359, winding of said relay 341, back contact 368 of the first main counting relay 331 and 30 front contact 366 of said stepping relay 362. Relay 341 is thereupon energized and closes a local locking circuit for its winding by way of contact 369. Upon the first deenergization of the stepping relay 362, back contact 367 is closed, whereupon a circuit is 35 completed for the first main counting relay 331 from battery 152, sequence switch contact 360, the winding of said relay 331, back contact 370 of the second auxiliary counting relay 342, front contact 371 of the first auxiliary counting relay 341 and said back contact 367 of the stepping relay. Relay 331 thereupon closes its front contact 372 which is connected to the first of a series of 40 controlling switches or keys 391 to 398 inclusive. If this first key had been depressed, a circuit would then have been completed for relays 363 and 364 by way of sequence switch contact 358, said controlling switch 45 or key 391 and said front contact 372 of the first named counting relay 331, whereupon the cut-off relay 363 would open at its back contact 373 the circuit of the stepping relay 362, while relay 364 would close a circuit 50 for the motor magnet 391 of the sequence switch by way of the front contact 374 of said relay 364 and sequence switch contact 357. It will be apparent that the intermittent energization and deenergization of the 55 stepping relay 362 will continue in the manner described to operate and lock up the counting relays in succession until the front contact, corresponding to contact 372 of some one of the main counting relays closes 60 a circuit for the cut-off relay 363; and this 65

closure will be determined in any case by the controlling switch or key which had been depressed. Thus if the eighth key 398 had been depressed, the stepping relay 362 would be energized eight times before the circuit 70 for the cut-off relay 363 would be closed and the sending of impulses to the sending relay would be stopped.

A reset relay 365 (Fig. 3) controls two front contacts 375 and 376 and a back contact 75 377, contact 375 being adapted to close a locking circuit for said relay in shunt of sequence switch contact 354, while contacts 376 and 377 are adapted to be connected to the motor magnet 391 of the sequence 80 switch, contact 376 when the sequence switch is in normal position, and contact 377 when it is in all other positions, 2 to 18 inclusive.

301 and 351 are the special sequence 85 switch contacts of Fig. 3 which correspond in function to contact 101 of the sequence switch of Fig. 1. A switch 378 is provided for the purpose of causing the sender sequence switch to be moved out of the second position. This contact may be operated manually at the time a controlling switch or key is depressed to determine the operation of the selector of Fig. 1. It may, however, and in practice would be operated automatically upon the closing of the controlling switch or key. It may be here stated that the complete arrangement of circuits and apparatus at the cord finder and sender for a large exchange system are not shown in 90 Fig. 3; that is to say, only so much thereof is shown as enters into the control of the cord circuit and selector mechanism of Fig. 1. In a large telephone exchange system, 95 of which the system herein disclosed is a 100 part, there would be several such selector mechanisms arranged to be operated in succession to establish a connection between subscribers' lines, and the sender mechanism would in such case comprise several sets of 105 controlling switches or keys representing the several digits of the numbers assigned to the subscribers' lines. In this application, however, the first or district switch only, and a single set of controlling switches or keys 110 therefor are shown.

In Fig. 4 there are shown the circuits of a trunk line and a called subscriber's line, together with the apparatus associated with said trunk line which enters in some respects 115 into the control of the selector mechanism and signaling apparatus of Fig. 1. The trunk line circuits are controlled in part by a sequence switch which is represented in this figure by a motor magnet 481, a driving disk 479, a roller 480 and contacts 401 to 411 inclusive, contact 401 being the special contact corresponding in function to contact 101 of Fig. 1. The trunk line when 120 extended to a subscriber's line may include 125 130

contacts of several successively operated selectors, the switch mechanism of which are not shown in the drawing. These are indicated, however, by contacts 441, 442 and 5 443. There may be interposed in the trunk line a repeating coil 414, windings 415 of which are included in that part of the trunk circuit connected to the terminals of the selector of Fig. 1, and windings 416 of 10 which are included, together with a battery 417, in that part of the trunk line which is connected directly to a called line 418 leading to a substation 419. Included in that 15 part of the trunk circuit which leads to the selector is a line relay 420, back contacts 421 and 422 of a battery control relay 423, and a battery 424. When the battery control relay 423 is energized, that part of the trunk circuit which leads to the selector is closed 20 at front contacts 425 and 426 but without including the battery 424. The winding of line relay 420 is shunted to voice currents by a condenser 427. This relay controls back and front contacts 428 and 429 respectively, 25 while battery control relay 423 controls in addition to the contacts mentioned, back and front contacts 430 and 431. The arrangement of local circuits controlled by these contacts of relays 420 and 423 is such that 30 the sequence switch, after it leaves its normal position, is under the joint control of said relays, the circuit of its motor magnet 481 being closed when said relays are simultaneously energized or simultaneously de- 35 energized. A supervisory relay 432 is included in that part of the trunk line which leads to the called line, said relay being adapted, when energized, to close contact 433 leading to one of the switch springs of 40 the sequence switch. It will be noted that in the twelfth position of the sequence switch, the circuit of the called line includes a ringing generator 434 and a winding 435 of a ringing control relay 436, this relay be- 45 ing adjusted to respond to ringing current only when the subscriber takes his telephone from its hook in answer to the call. When so energized, relay 436 closes a locking circuit by way of front contact 437 and a 50 second winding 438 of said relay, this circuit including also the winding of supervisory relay 432. Upon entering the 17th position, the sequence switch closes contact 411 in circuit with a test contact 412 and an 55 electromagnet 413. Contact 412 would be closed simultaneously with the selector contacts 442 and the energization of the electromagnet 413 would be the means of restoring the selector and thus causing the open- 60 ing of the trunk line and local test circuits at said contacts 442 and 412. Similarly the de-energization of an electromagnet 444 in test wire 175 would be the means of restoring a selector controlling contacts 441 in the 65 trunk line.

Before describing the complete mode of operation of the system, it may be stated with regard to the sequence switches that they are in each case advanced from position to position to control circuits for causing a 70 particular operation of the mechanism associated therewith and that the several positions of the sequence switches are thus characterized and may be referred to either by the conditions which exist or by the operations which take place in those positions. Thus the positions of the selector sequence switch of Fig. 1 may be referred to as follows: 1, normal; 2, awaiting pressing of 75 controlling key or switch; 3, transmitting impulses for selection; 4, trunk hunting; 5, return on knock-down connection; 6, 80 ringing; 7, talking; 8, 11 or 14, returning apparatus at end of trunk line on disconnect; 9, awaiting return of trunk line apparatus; 10, 85 return of switch. In a similar way the positions of the listening key sequence switch are: 1, normal; 2, moving selector sequence switch off normal and moving another listening key from 90 listening position; 5, listening, wipe out and flash back; 6, energizing knock-down relay on an incompletely pull down connection; 9, off listening; 1, releasing selector apparatus 95 on disconnect. The cord finder sequence switch positions are: 1, normal; 2, hunting cord; 4, moving sender sequence switch off normal; 15, awaiting completion of selecting operations. The sender sequence switch positions are: 1, normal; 2, awaiting pressing of controlling key or switch; 3, receiving impulses for 100 selection; 18, awaiting completion of selecting operations. The trunk line sequence switch positions are: 1, normal; 12, ringing; 13, talking; 17, 105 releasing selector apparatus. In the operation of the system, a subscriber located at substation 501 of line 502 (Fig. 5) desiring connection with another subscriber, located, say, at substation 419 (Fig. 4) may take his receiver from its switch hook and cause the operation of the line signal 508 in the usual manner. Noting 110 the signal, an operator inserts one of the cord circuit plugs—say plug 134—in the calling line spring jack 503. The insertion of the plug completes a local circuit from the neutral or middle point of battery 152 (Fig. 1) through the winding of cord relay 135, 115 sleeve of plug 134, sleeve of springjack 503, winding of cut-off relay 506 to the free pole of said battery 152. The cord relay and the cut-off relay are energized, the latter opening 120 the normal connections of the line circuit to the line relay 507 and to ground, causing the extinguishment of the line signal 508. A circuit is now completed for the calling 125 subscriber's line from battery 150 (Fig. 1) through one half of winding 149 of repeating 130

coil 148, conductor 189, the listening key sequence switch contact 212, conductor 182, answering supervisory relay 141, ring contact of plug 134, ring spring of jack 503, line 5 502 through substation and back to tip spring of jack 503, tip contact of plug 134, conductor 181, listening key sequence switch contact 209, conductor 190, the other half of winding 149 to the ground pole of said battery 150. Battery 150 thus supplies current to energize the transmitting telephone at the calling subscriber's station.

The energization of the cord relay 135 which follows the insertion of the plug 15 causes contacts 138 and 139 to be closed. Contact 139 controls a local circuit for the answering supervisory lamp signal 140, but this lamp is not lighted at this time because the circuit is opened at the back contact 142 20 of the supervisory relay 141 which is energized by current in the circuit of the calling line. The closing of front contact 138, however, completes a circuit for the motor magnet 281 of the listening key sequence switch, 25 this circuit including battery 152 (Fig. 2), the winding of motor magnet 281, listening key sequence switch contact 216 and said front contact 138 of the cord relay 135. The listening key sequence switch is thereupon 30 caused to move from the first to the fifth or "listening" position. In passing positions 2 to 4 inclusive, a ground connection is made to the common conductor 227 which completes a circuit for any other listening key 35 sequence switch which may happen at that time to be in the fifth position. Such a circuit may be traced in Fig. 5 as follows: From battery 152, the winding of the motor magnet of a listening key sequence switch 40 in listening position, say motor magnet 291, sequence switch contact 262 of said listening key, conductor 227 and sequence switch contact, say 203, of the listening key of the cord circuit being taken for use. The motor 45 magnet 291 of the sequence switch in the fifth or listening position is now energized and causes the said sequence switch to move out of the said position into the ninth or off-listening position, where it rests until the 50 connection therethrough is taken down by the removal of plug 244 from the springjack of the connected line. As the listening key sequence switch of the cord circuit now taken for use moves into the fifth position, contacts 55 210, 211, 213 and 214 are closed to connect the operator's telephone set in a bridge of the cord circuit, while contacts 209 and 212 are opened. The cord circuit is now closed through the contacts mentioned and the normal contacts 228 of the ring back key 229. The circuit to the calling subscriber's line is not interrupted even momentarily by this change in the cord circuit because of the continuity operation of the sequence switch contacts 209, 210 and 211, 212.

As the listening key sequence switch (Fig. 2) moves out of normal position, contact 215 is closed, thereby completing a circuit for the selector sequence switch as follows: Battery 152 (Fig. 1), motor magnet 81 of the selector sequence switch, contact 108 of said sequence switch, conductor 187, said contact 215 of the listening key sequence switch and the front contact 138 of cord relay 135 to ground. The selector sequence switch is thereupon caused to move into the second position.

A number of contacts are closed by the selector sequence switch as it enters the second position as follows: Contact 109, 80 which is connected to the listening key sequence switch contact 207; contact 116 which connects the winding of knock-down relay 159 to the master wipe-out key 225 through listening key sequence switch contact 204 now closed; contacts 121, 125 and 110 which connect line relay 153 in a loop circuit leading through conductors 192 and 193 to stationary terminals 314 and 315 of the cord finder (Fig. 3); contacts 106, 102, 90 and 104 which close connections from back contact 161 of knock-down relay 159 to conductors 194, 196 and 197, respectively, leading to stationary terminals 316 and 318 and sequence switch contact 308 respectively of the cord finder; contact 131 which places a ground connection to conductor 183 leading to listening key sequence switch contact 205; contact 126 which places a ground connection to an armature of the knock-down relay 159; and contact 112 which connects the motor magnet 81 of the selector sequence switch to front contact 156 of line relay 153.

The closing of the selector sequence switch contact 104 completes a circuit for the motor magnet 379 of the cord finder sequence switch, whereupon said sequence switch moves from normal to the second position in which a circuit is closed for the cord finder motor magnet 323 by way of sequence switch contact 304 and back contact 326 of test relay 325. The brush carriage of the cord finder is thereupon caused to move the brushes 309 to 313 over the rows of stationary terminals. When the brushes reach the terminals 314 to 318, which are connected to the cord circuit of Fig. 1, which is the one taken for use, a circuit will be completed for the test relay 325 by way of the cord finder sequence switch contact 302, conductor 386, brush 313, terminal 318, conductor 196, selector sequence switch contact 102 and back contact 161 of knock-down relay 159 to ground. The test relay thereupon opens at its back contact 326 the circuit of the cord finder motor magnet 323 and closes at its front contact 327 a circuit for the holding magnet 324, this latter circuit including sequence switch contact 306, closed in two positions, 2 and 3, of said sequence switch. 120

The cord finder is thus caused to stop with the brushes 309 to 313 inclusive resting in contact with the terminals 314 to 318 inclusive, respectively, and conductors 192 to 196 inclusive are now extended to conductors 382 to 386 inclusive of the cord finder and sender. The closing of front contact 327 of test relay 325 also completes a circuit for the motor magnet 379 of the cord finder sequence switch, this circuit including sequence switch contact 307. Said sequence switch is thereupon moved from the second to the fifteenth position.

Upon entering the fourth position, the cord finder sequence switch closes a circuit for test relay 325 as follows: From battery 152 to winding of said test relay 325, cord finder sequence switch contact 303, conductor 387, the winding of reset relay 365 associated with the sender, sender sequence switch contact 354 (now closed in normal position), conductor 384, brush 311, terminal 316, conductor 194, selector sequence switch contact 106 and back contact 161 of knock-down relay 159 to ground. Reset relay 365 is energized and it and test relay 325 remain energized as the cord finder sequence switch moves to the fifteenth position. The back contact 326 of the test relay therefore is held open and said sequence switch comes to rest in the fifteenth position.

The energization of the reset relay 365 causes the sender sequence switch to move from normal to its second position, a circuit being closed for the motor magnet 391 by way of sender sequence switch contact 352 and front contact 376 of said reset relay 365. The circuit for the test relay 325 and reset relay 365 remains closed, when the sender sequence switch moves out of normal position, through a locking contact 375 of said reset relay.

The operations which occur as above stated upon the insertion of an answering plug into the springjack of a calling line, occupy but a very brief interval of time. The cord finder may be constructed to move with great rapidity, the holding magnet insuring that the brush carriage will stop at the terminals of the cord circuit which is taken for use. The selector sequence switch is now in the second position, the listening key sequence switch in the fifth position, the cord finder sequence switch in the fifteenth position and the sender sequence switch in the second position. In the meantime the operator may inquire of the calling subscriber the connection that he desires, and upon learning the number of the line wanted, she may immediately depress controlling switches or keys corresponding to the digits of that number. It is assumed in the system herein described that a single selector switch is to be operated under the control of the keys. The operator will

therefore depress but one key and it may be assumed that this is key 398. At the same time contact 378 may be closed to cause the sender sequence switch to move out of the second position into the third in which the sending operation takes place.

As the sender sequence switch moves into the third position, a circuit is completed including line relay 153 of the cord circuit (Fig. 1) and stepping relay 362 of the sender (Fig. 3) as follows: From battery 152 (Fig. 1) through the selector sequence switch contact 121, the winding of said relay 153, selector sequence switch contact 125, conductor 192, cord finder terminal 314, brush 309, conductor 382, sender sequence switch contact 361, stepping relay 362, back contact 373 of cut-off relay 363, conductor 383, cord finder brush 310, terminal 315, conductor 193 and selector sequence switch contact 110 to ground.

The line relay 153 and the stepping relay 362 are energized in this circuit, the latter closing a circuit for the first auxiliary counting relay 341 which becomes locked and closes a contact in the circuit of the first main counting relay 331, which circuit is then ready to be completed upon the subsequent de-energization of the stepping relay. The energization of the line relay 153 completes a circuit for the selector sequence switch motor magnet 81 by way of the contact 112, the front contact 156 of said line relay 153 and the back contact 161 of knock-down relay 159. The selector sequence switch thereupon moves into the third position in which the brush selector is operated and in which impulses are transmitted over the sender circuit to the stepping relay 362.

The selector sequence switch upon reaching the third position, closes a circuit for the motor magnet 68 of the brush selector as follows: From battery 152 through the winding of said motor magnet 68, sequence switch contact 129, front contact 156 of line relay 153 and back contact 161 of the knock-down relay 159. The movement of the brush selector causes arm 56 to make intermittent connection with contact 60 and thus to intermittently short-circuit the stepping relay 362 in the circuit previously traced for that relay and line relay 153. The line relay 153, however, remains energized until the sender circuit is finally opened by the operation of cut-off relay 363, which occurs when its circuit is completed through the depressed key 398, whereupon said line relay is de-energized, opening the circuit of the motor magnet 68 of the brush selector and closing at its back contact 155 a circuit for the motor magnet 81 of the selector sequence switch by way of switch contact 113. The brush selector is thus caused to stop with one of its fingers 41 pointing in the direction of the brush carriage and in

line with the travel of the latch 32. At the same time the selector sequence switch moves out of the third position into the fourth, in which the brush carriage is advanced to hunt over the stationary terminals for an idle trunk line.

It will be noted that relay 364 of the sender apparatus is energized in the same circuit with cut-off relay 363, relay 364 closing its front contact 374 and completing a circuit for the motor magnet 391 of the sender sequence switch, whereupon the said sequence switch moves out of the third position and on to the eighteenth. In passing 15 out of the third position, the counting relays which had been operated in succession and locked in local circuits, are released by the opening of sequence switch contacts 359 and 360. Also the circuit of the stepping relay 362 is held open by the opening of the contact 361, after the sender sequence switch leaves the third position.

Referring again to Fig. 1, it will be noted that the following contacts are closed in the 25 fourth position of the selector sequence switch: Contacts 107 and 105 in the test circuit, and contact 103 in a conductor connected to the armature of the motor control relay 166. The closing of said contact 30 103 completes a circuit for the motor magnet 62 of the brush carriage, which circuit includes back contact 170 of said motor control relay 166, said sequence switch contact 103 and back contact 161 of the knock-down relay 159. The brush carriage is thereupon caused to rotate and a set of three brushes 23, 24 and 25 are released from the latch 32 as the brush carriage passes the brush selector and said latch strikes the finger 41. The movement of the brush carriage continues until the test brush 25 makes contact with a test terminal 29 of an idle line, whereupon test relay 165 is energized, closing its low resistance winding 168 in shunt 45 of its high resistance winding 167, and causing an increased flow of current in the test circuit, whereby said line will thereafter test busy to other selectors. A moment after the brush 25 touches terminal 29, a short-circuit by way of conductor 172, spring 52, arm 72 and ground plate 50, about the motor control relay 166, which exists while the brushes are passing between terminals is broken and said relay 166 is energized, opening 50 at its back contact 171 the circuit of the motor magnet 62 and closing at its front contact 171 a circuit for the holding magnet 65. This last mentioned circuit may be traced from battery 152, through said holding magnet 65, said front contact 171 of relay 166, sequence switch contact 103 and back contact 161 of knock-down relay 159. The brush carriage is thus caused to stop 60 with the brushes 23, 24 and 25 in contact 65 with terminals 27, 28 and 29 of an idle

trunk line, comprising line conductors 173, 174 and test conductor 175. The line conductors 173 and 174 may be extended as shown in Fig. 4 through contacts of other selector mechanisms to a repeating coil 414 70 located at a distant or B office. The energization of motor control relay 166 also caused the selector sequence switch to move out of the fourth position into the sixth, a circuit having been closed for the motor 75 magnet 81 of said sequence switch by way of the front contact 171 of said relay 166, sequence switch contact 103 and back contact 161 of the knock-down relay 159.

The selector sequence switch may remain 80 in the sixth position until the selector switch mechanisms other than the one shown in Fig. 1 have been successively operated under the control of the sender and have closed contacts 441, 442, 412 and 443. According 85 to the arrangement shown, however, in which there is but one selector, no time interval need be considered for such operations, and a circuit is closed for the motor magnet 81 of the selector sequence switch 90 by way of contact 112, conductor 195, cord finder terminal 317, brush 312, conductor 385, sender sequence switch contact 355, said sequence switch being at this time in the eighteenth position, conductor 384, brush 311 95 and terminal 316 of the cord finder, conductor 194, selector sequence switch contact 106 and back contact 161 of knock-down relay 159. The selector sequence switch thus moves on to the seventh position in which 100 a circuit for the motor magnet 81 is closed by way of the front contact 171 of relay 166, sequence switch contact 103 and back contact 161 of the knock-down relay 159. The sequence switch therefore continues to the 105 eighth position, wherein a circuit is closed over the trunk line as follows: Battery 424 (Fig. 4) back contact 421 of the battery control relay 423, line relay 420, one half 110 of winding 415 of repeating coil 414, contacts 442 and 441 in the trunk line, conductor 173, terminal 27 of the selector, brush 23, conductor 176, one-half of winding 151 of repeating coil 414, selector sequence switch contacts 119 and 120, line relay 153, the 115 other half of winding 151, conductor 177, brush 24, terminal 28, conductor 174, contacts 441 and 442 in the trunk line, the other half of winding 415 of repeating coil 414 and back contact 422 of battery control relay 423 to the ground pole of battery 424. Line relays 153 (Fig. 1) and 420 (Fig. 4) 120 are energized in this circuit, the former closing a circuit for the motor magnet 81 of the selector sequence switch by way of sequence switch contact 112, front contact 156 of said line relay 153 and back contact 161 of the knock-down relay 159. The selector sequence switch thereupon moves into 125 the ninth position, in which the trunk line 130

circuit remains closed through contacts 119 and 120.

In the seventh position the selector sequence switch closes at contact 128 a local circuit for the restoration of the brush selector.

As the selector sequence switch moves out of the sixth position, the cord finder test relay 325 and the sender reset relay 365 are deenergized, the circuit heretofore traced including their windings being opened at contacts 112 and 106. The deenergization of the test relay 325 causes the cord finder sequence switch to move from the fifteenth position to normal, a circuit for its motor magnet 379 being closed by way of sequence switch contact 305 and back contact 326 of said test relay 325. The deenergization of the sender reset relay 365 causes the sender sequence switch to move from the eighteenth position to normal, a circuit for its motor magnet 391 being closed by way of sequence switch contact 353 and back contact 377 of said reset relay 365. The brush carriage of the cord finder remains in the position in which it had been placed to connect the sender with the cord circuit, but it is otherwise restored to normal condition and is ready to associate the sender, which is now also in normal condition, with any other cord circuit that may be taken for use. The ringing lamp signal 157 (Fig. 1) is lighted, its circuit being closed by way of sequence switch contact 114, front contact 156 of line relay 153 and back contact 161 of knock-down relay 159.

The energization of trunk line relay 420 (Fig. 4) causes a circuit to be closed from battery 424 by way of motor magnet 481, sequence switch contact 402 and front contact 429 of said relay 420, whereupon the trunk line sequence switch is moved from the first or normal position to the twelfth, which is the ringing position. As the sequence switch enters the twelfth position, a circuit is closed for the ringing generator 434 by way of sequence switch contact 406, contact 443, over the line circuit to substation 419, and there through the condenser and signal bell, returning by way of the other side of the line, contact 443, sequence switch contact 408 and winding 435 of the ringing control relay 436. The signal bell is sounded by current from the ringing generator over this circuit, and the ringing control relay is adjusted to be irresponsive to such current. The contacts 443 in the circuit to the called station may be the contacts of a final selector switch, the mechanism of such switch and of other similar switches in the trunk line circuit not being shown in the system herein described.

Upon the response of the subscriber to the ringing of the bell at the called station 419, relay 436 is energized, whereupon a

circuit is closed from battery 417 by way of one-half of winding 416 of repeating coil 414, supervisory relay 432, winding 438 and front contact 437 of said relay 436 and sequence switch contact 410 to ground. The 70 armature of relay 436 is prevented from vibrating by reason of its winding 438 being included in this circuit. The supervisory relay 432 is now energized and a circuit is closed for the motor magnet 481 of 75 the trunk line sequence switch by way of sequence switch contact 404 and front contact 433 and of said supervisory relay 432. The trunk line sequence switch is thereupon caused to move from the twelfth into the 80 thirteenth position in which the ringing circuit is opened at sequence switch contacts 406 and 408 and the circuit to the called subscriber's station is closed at sequence switch contacts 407 and 409. A circuit is 85 also closed in the thirteenth position from battery 424 through the winding of relay 423, sequence switch contact 405 and contact 433 of supervisory relay 432, whereupon said relay 423 switches the battery 90 424 out of circuit of the trunk line by opening its back contacts 421 and 422 and closes the trunk line circuit again without battery through its front contacts 425 and 426. The removal of battery 424 from the trunk line 95 circuit causes the immediate deenergization of trunk line relay 420 which then opens its front contact 429 and closes its back contact 428. As the battery control relay 423 and the trunk line relay 420 are thus affected at 100 the same or almost the same instant, the motor magnet 481 is not energized and the trunk line sequence switch remains in the thirteenth position. The switching of battery 424 out of the trunk line circuit, however, causes the deenergization of line relay 105 153 (Fig. 1) at the distant or cord circuit end of the trunk line, whereupon a circuit is closed for the selector sequence switch which is now in the ninth position from 110 battery 152 through motor magnet 81, sequence switch contact 113, back contact 155 of said line relay 153 and back contact 161 of knock-down relay 159 to ground, whereupon the selector sequence switch moves 115 from the ninth to the tenth or "talking" position. The ringing lamp signal 157 is extinguished and is prevented from thereafter being lighted by the opening of sequence switch contact 114, while the supervisory lamp signal 158 is immediately placed in position for subsequent operation, when the line relay 153 shall become energized, by the closing of sequence switch contact 115. The trunk line remains closed 120 at sequence switch contacts 119 and 120 and the apparatus is now in position for telephonic communication from the calling station 501 to the called station 419.

At the termination of the period of con- 130

versation, each subscriber will ordinarily replace his receiver upon its switch hook, whereupon supervisory lamp signals 140 and 158 will be lighted, the former by the de-
 5 energization of supervisory relay 141 in the answering plug portion of the cord circuit and the latter by reason of the energization of line relay 153 in the circuit of the trunk line, which energization is caused in the fol-
 10 lowing manner: The opening of contact 433 of supervisory relay 432 (Fig. 4) opens the circuit of the battery control relay 423 which in turn switches battery 424 again into the trunk line circuit and causes the
 15 energization of relays 420 and 153, the latter operating thereupon to close the circuit of the supervisory lamp signal 158. Relay 423 being deenergized and relay 420 energized at the same or almost the same instant, the
 20 circuit of motor magnet 481 of the trunk line sequence switch remains open just as it did upon the reverse operation wherein the supervisory relay 432 was energized upon the response of the called subscriber.
 25 In response to the operation of the supervisory signals 140 and 158, the operator may disconnect the line and cause restoration of the apparatus by withdrawing the answering plug 134 from the springjack 503 of the
 30 calling line. At this time the listening key sequence switch may be either in the fifth or in the ninth position. It will in most cases be in the ninth, which is the "off-listening" position, because the operator would be un-
 35 likely to leave her telephone set connected in the circuit during the ringing and conversation periods. The withdrawal of the plug causes the deenergization of cord relay 135, this relay thereupon operating to
 40 open its front contacts 138 and 139 and to close its back contacts 136 and 137. The opening of front contact 139 does not cause the answering supervisory lamp signal 140 to be extinguished because said contact 139
 45 is now shunted by sequence switch contact 130, this contact remaining closed until the sequence switch passes the eighteenth position in its return to normal. The signal serves therefore not only to indicate the
 50 condition of the calling line when the connection is made thereto, but also to indicate the full return of the selector and mechanism associated with the cord circuit upon the removal of the plug to disconnect the
 55 lines, and thus to warn the operator against the use of the cord circuit for a new connection until it is in normal condition.
 Assuming that the listening key sequence switch is in the ninth position when the plug
 60 is withdrawn to disconnect, a circuit is then closed for the motor magnet 281 of the listening key sequence switch by way of sequence switch contact 206, conductor 185 and back contact 136 of cord relay 135 to ground, whereupon said listening key sequence switch moves from the ninth position to normal. Upon reaching the normal position, a circuit is closed for the motor magnet 81 of the selector sequence switch by way of contact 109, conductor 186, the listening key sequence switch contact 207, conductor 185 and back contact 136 of cord relay 135 to ground, whereupon the selector sequence switch advances from the tenth to the fif-
 65 teenth position.
 Upon leaving the tenth position, the selector sequence switch opens at contacts 119 and 120 the circuit of the trunk line which remains open until the sequence switch enters the fourteenth position. The opening of the circuit causes the deenergization of trunk line relay 420 (Fig. 4), whereupon a circuit is closed for motor magnet 481 from battery 424 through the winding of said magnet, sequence switch contact 403, back contact 430 of relay 423, and back contact 428 of relay 420 to ground. The trunk line sequence switch thereupon moves from the thirteenth position to normal. In the seventeenth position of the trunk line sequence switch the local circuit of electromagnet 413 is closed at contact 411, whereby the circuit of the trunk line is opened at contacts 442, the local circuit being also opened at contact 412. Line relay 153 (Fig. 1) will now close its back contact 155, whereupon (the selector sequence switch being now in the fifteenth position) a circuit is closed for the motor magnet 81 of the sequence switch by way of sequence switch contact 113, said back contact 105 and back contact 161 of knock-down relay 159. The selector sequence switch thereupon moves from the fifteenth to the seventeenth position. Upon leaving the fifteenth position, the test circuit which leads from battery 424 (Fig. 4) including relays 166 and 165 is opened at sequence switch contact 105, whereupon relay 165 releases its armature, opening the low resistance path at contact 169, so that when sequence switch contact 105 is again closed in the seventeenth position the test circuit remains open at said contact 169. Upon entering the seventeenth position a circuit is closed for the motor magnet 62 of the selector by way of back contact 170 of the motor control relay 166, sequence switch contact 103 and sequence switch contact 111 to ground, whereupon the brush carriage of the selector is returned to normal. It will be noted that as the sequence switch enters the seventeenth position, the knock-down relay 159 is energized by way of sequence switch contact 127, so that battery 152 is connected through front contact 163 of said relay 159 and resistance 164 to the normal stop plate 46 of the selector. Therefore when the selector reaches normal and the contact lever 43 en-

gages the normal stop plate 46, a circuit is closed for the motor control relay 166 from said stop plate 46 to said lever 43 and through conductor 172, said relay 166 and 5 sequence switch contacts 105 and 111 to ground. Relay 166 is thereupon energized, opening at its back contact 170 the circuit previously closed for motor magnet 62 and closing at its front contact 171 circuits for 10 the holding magnet 65 and the motor magnet 81 of the selector sequence switch, these circuits being substantially the same as those previously traced upon the operation of the selector to make connection with an idle 15 trunk line. The selector is thus caused to stop when it reaches normal and its sequence switch is caused to move from the seventeenth position to normal. In leaving the eighteenth position the circuits closed at 20 sequence switch contacts 130, 127 and 111 are opened, and the cord circuit and selector are now in position for use in establishing another connection.

The opening of the test circuit at contact 25 105 when the selector sequence switch leaves the fifteenth position causes the deenergization of electromagnet 444 and thereby the opening of contacts 441 in the trunk line.

It has heretofore been stated that if one 30 listening key sequence switch of an operator's position is in the fifth (the listening) position and a plug is inserted to establish another connection, such listening key sequence switch will be moved to the "off-listening" position. The same result may be secured by manipulating the master listening out key 224, this key being arranged to place a ground on the common conductor 227, thereby closing a circuit for the motor 35 magnet of any listening key sequence switch in the operator's position which may be in the fifth or listening position and causing said sequence switch to move to off-listening position. If the operator should desire to 40 listen in on a connection, when her listening key sequence switch for that particular connection is in the ninth or "off-listening" position, she may manipulate the individual listening-in key 223, which is arranged to 45 close a circuit in that position for the motor magnet of said sequence switch. The sequence switch will in such case be moved from the off-listening position to normal, and upon reaching normal position, a circuit 50 will be closed for the motor magnet, say 281 (Fig. 2), by way of sequence switch contact 216 and front contact 138 of cord relay 135, so that the listening key sequence switch 55 will move continuously from the ninth to the fifth position without stopping at normal.

The master flash-back key 226 may be used 60 only when the listening key sequence switch is in the fifth or listening position and the selector sequence switch is in the ninth or

tenth position. It may be used to operate a signal device in trunk lines leading to a manual switchboard, to any of which lines connection may be made by the selector of Fig. 1. This key merely bridges battery 152 70 on the circuit of said trunk line, the connection being made to conductors 176 and 177 by way of the selector sequence switch contacts 123 and 117.

The master wipe-out key 225 is provided 75 for the purpose of causing restoration of the mechanism associated with the cord circuit and selector before connection with the called line has been fully established. It will be noted that the operation of this key, 80 places a ground upon conductor 188 through sequence switch contact 204 (closed only in the fifth or listening position of the listening key sequence switch), this conductor 188 leading through the selector sequence switch 85 contact 116 (closed in positions 2 to 6, inclusive) to the winding of knock-down relay 159. Thus the master wipe-out key may be manipulated to energize the knock-down relay and at any time when the listening key 90 is in listening position and before the selecting operation is completed. The knock-down relay will in such case remain energized until the selector sequence switch leaves the tenth position, its locking circuit 95 being closed by way of front contact 160 and sequence switch contact 126. And it will be noted also that when the knock-down relay is thus energized a circuit is closed at front contact 162 for the motor magnet 81, 100 this circuit being completed in several positions of the selector sequence switch by way of contact 109. Therefore, should the wipe-out key 225 be actuated while the selector sequence switch is in the second or 105 third position, said sequence switch will be caused to move continuously from positions 2 or 3 by positions 4, 6, 7, 8, 9 and 10, the following circuit changes taking place to bring this about, the selector switch remaining at normal: The sequence switch contact 109 being closed in the 2nd and 3rd positions a circuit is completed for the motor magnet 81 by way of this sequence contact and front contact 162 of knock-down relay 159, whereupon the sequence switch will be moved to the 4th position. In this position the motor magnet 81 is maintained energized in a circuit by way of front contact 171 of relay 166 and sequence contacts 103, 111, the circuit of 110 the motor control relay 166 being now closed by way of front contact 163 of knock-down relay 159 and stop plate 46. The sequence switch is thereupon moved to the 6th position, wherein a circuit is completed for the 115 said motor magnet by the closing of contact 109 and the sequence switch advances to the 7th position. A circuit is now completed for said motor magnet by the closure of sequence contacts 108, 111, and front contact 130

171 of the motor control relay, whereupon the sequence switch advances to the 8th position, wherein by reason of the closure of contact 109 said switch runs continuously by 5 the said position and also the 9th and 10th positions. Upon leaving the 10th position the selector sequence switch will go on to the 15th position, wherein a circuit will be closed for its motor magnet by way of sequence 10 switch contact 113, back contact 155 of line relay 153, back contact 161 of knock-down relay 159, which relay is now deenergized due to the opening of sequence contact 126 when the sequence switch left the 10th position. 15 The sequence switch thereupon moves on to the 17th position, wherein the knock-down relay 159 is again energized by the closing of sequence switch contact 127, and since the motor control relay 166 is also energized over the circuit heretofore traced by 20 way of contact 163 of the knock-down relay, conductor 172 and the normal stop plate 46, the motor magnet 81 is again energized in a circuit by way of front contact 171 of the 25 said motor control relay and sequence switch contacts 103 and 111. The sequence switch therefore moves past the 17th position and returns to normal.

Should the wipe-out key 225 be operated 30 while the selector sequence switch is in the 4th position, that is, while the selector is hunting an idle trunk, the trunk hunting operation will continue without interruption because contact 109 is open in that position 35 and a circuit for the motor magnet 62 of the selector is maintained closed by way of back contact 170 of relay 166 and the sequence switch contacts 103 and 111. When the idle line is found, however, and the sequence switch moves on to the 6th position, the knock-down relay being energized, the sequence switch will advance to the 7th position by the closure of sequence contact 109, from which position the selector will be 40 caused to return to normal, the following circuit changes taking place to bring this about: Since back contact 161 of the knock-down relay was opened upon the depression of the wipe-out key, and sequence contact 45 111 opened as the selector sequence switch left the 4th position, no circuit was retained for relays 165 and 166 and they were consequently deenergized, the contact 169 being thereupon opened. Upon the arrival of the 50 sequence switch at the 7th position, a circuit was closed for the motor magnet 62 of the selector by way of the back contact 170 of the motor control relay 166 and sequence switch contacts 103 and 111. Upon reaching 55 normal, the selector closes the circuit for relay 166 heretofore traced by way of conductor 172 and stop plate 46, and the restoration of the sequence switch to normal takes place in the manner already stated.

The following means is provided for energizing the knock-down relay and restoring the mechanism of the selector in the case of an incompletely connection. Contact 205 of the listening key sequence switch is closed in positions 6 to 8 so that if the plug 134 65 is withdrawn from the spring-jack of the calling line and the listening key sequence switch is moved out of listening position, 5, by reason of the insertion of another plug, these events occurring before the selector 70 switch has moved beyond the sixth position, a circuit will be completed for the knock-down relay by way of the selector sequence switch contact 116, conductor 188, the listening key sequence switch contact 205, conductor 183, and back contact 137 of cord relay 135. Restoration of the selector mechanism will follow in the manner already described. 80

The mode of operation of the supervisory lamp signals 140 and 158 is the same as that of ordinary supervisory signals in telephone exchange systems, except that these signals are in the present system also caused to indicate the condition of the switching mechanism. It will be noted that lamp signal 140 90 is controlled by the usual supervisory relay 141, a contact 142 of said relay being closed in the circuit of the lamp when the relay is deenergized. This circuit is arranged to be completed either by way of front contact 95 139 of the cord relay 135, or by way of contact 130, which latter contact is closed in positions 3 to 18 of the selector sequence switch. So long as the answering plug 134 is within the springjack of a calling line, 100 the lamp signal 140 will respond in the usual way to the opening and closing of the hook switch at the subscriber's station, and when the plug is withdrawn the circuit of this signal will be completed continuously by 105 way of contacts 130 and 142 until the sequence switch leaves the 18th position and returns to normal. This lamp signal therefore serves, when the plug is withdrawn, to indicate to the operator that the mechanism 110 associated with the plug has not been restored to normal condition. As long as the lamp remains lighted, the operator will understand that this plug should not be used for another connection, but when it goes out 115 she will understand that it may then be taken for use. Lamp signal 158 performs a function similar to that of lamp 140. Its circuit is completed by way of sequence switch contact 106 and back contact 161 of 120 the knock-down relay 159 while the sequence switch is in positions 2 to 6 inclusive. It will be remembered that this sequence switch moves beyond the 6th position only after the selector switch mechanism has completed connection with the called line. 125 The signal is extinguished as soon as the connection is made and the operator will under-

stand as long as the lamp remains lighted, that for some reason or other the connection is not completed.

I claim:-

- 5 1. In a telephone system, the combination with a plurality of telephone lines, of a connecting circuit adapted to be connected with any of said lines in response to a call thereon, a sequence switch for each of said connecting circuits, an operator's set for a plurality of said connecting circuits, and a key under the control of the operator, adapted by its actuation to start said sequence switch to cause the connection of said connecting circuit with said operator's set.
- 10 2. In a telephone system, the combination with a plurality of telephone lines, a plurality of connecting circuits any one of which may be connected with any one of said lines in response to a call on a line, a sequence switch for each of said connecting circuits, an operator's set common to all of said connecting circuits, a pair of keys under the control of the operator, one for starting a sequence switch to connect a connecting circuit with the operator's set, and the other to continue the motion of said sequence switch to disconnect the connecting circuit from the operator's set.
- 15 3. The combination with a plurality of switching mechanisms each having a controlling electromagnet, of a conductor common to the several mechanisms, means for connecting any one of the electromagnets with said conductor and switches one for each of said mechanisms adapted upon the operation thereof to complete a circuit by way of said conductor through the connected electromagnet.
- 20 4. The combination with a plurality of switching mechanisms each having an electromagnet and a local controlling circuit therefor, of a conductor common to the several mechanisms, switches one for each of said mechanisms adapted in one position of said mechanism to connect the electromagnet thereof in a partially completed circuit with said conductor, and other switches one for each mechanism adapted in the movement thereof to complete the circuit of said conductor.
- 25 5. The combination with a plurality of sequence switch mechanisms each having a controlling electromagnet, of a source of current, a conductor common to the several mechanisms and normally disconnected from said source of current, switches one for each of said mechanisms and adapted in an advanced position thereof to connect the electromagnet thereof with said conductor, and other switches one for each mechanism adapted during the initial movement thereof to complete a circuit for said source of current by way of said conductor and any connected electromagnet.
- 30 6. The combination with a plurality of switch mechanisms each having a controlling electromagnet of individual circuits for each mechanism and a common circuit adapted to be extended to any of said individual circuits by the corresponding switching mechanism, a conductor common to the several mechanisms and adapted to be connected in circuit with any of said electromagnets, and switches one for each mechanism adapted upon the operation thereof to complete the circuit of said conductor. 70
7. In a telephone exchange system, the combination with a plurality of telephone lines, connecting switches for extending the circuits of said lines and a telephone set, of means under the control of any one of said connecting switches for connecting said telephone set in circuit with a telephone line, and means operative thereafter under the control of any other of said connecting switches for disconnecting said telephone set from the circuit of said line. 80
8. The combination with a plurality of telephone lines, connecting switches for extending the circuits of said lines and a telephone set, of means operating under the control of one of said connecting switches to connect said telephone set in circuit with a telephone line, and means operating thereafter under the control of another of said connecting switches to disconnect said telephone set from the circuit of said line and to connect it in circuit with another of said lines. 90
9. In a telephone exchange system, the combination with a telephone line, a connecting circuit therefor, a line switch adapted to extend the circuit of said line to said connecting circuit, and a telephone set, of means controlled by said line switch for connecting said telephone set in circuit with said line, another telephone line, connecting circuit and line switch and means controlled by the last mentioned line switch adapted to disconnect said telephone set from the circuit of the first mentioned line and to connect it in circuit with the last mentioned line. 100
10. In a telephone exchange system, the combination with a plurality of telephone lines, a plurality of connecting circuits therefor, line switches adapted to extend the circuits of said lines to said connecting circuits and an operator's telephone set, of a device associated with each of said connecting circuits adapted upon the closure of the associated line switch to connect said telephone set in circuit with the connected line and to disconnect it from any other line with which it previously may have been connected. 110
11. In a telephone exchange system, the combination with a telephone line, a cord circuit, a plug and jack switch for extend- 120
- 125
- 130

ing the circuit of said line to said cord circuit, and an operator's telephone set, of a sequence switch, a motor magnet for said sequence switch, a circuit for said motor magnet completed in the act of closing said plug and jack switch, said sequence switch being adapted thereupon to connect said telephone set in circuit with said line, another telephone line, cord circuit, plug and jack switch, sequence switch and motor magnet, and a circuit for the last mentioned motor magnet completed in the act of closing the last mentioned plug and jack switch, the last mentioned sequence switch being adapted thereupon to disconnect said telephone set from the first mentioned circuit.

12. In a telephone exchange system, the combination with a plurality of telephone lines, a plurality of connecting circuits, line switches for extending the circuits of said lines to said connecting circuits, and an operator's telephone set, of sequence switches one for each of said connecting circuits, each sequence switch being adapted upon the closure of a line switch to connect said telephone set with the associated connecting circuit and being adapted also upon the closure of any other of said line switches to disconnect said telephone set from said connecting circuit.

13. In a telephone exchange system, the combination with a telephone line, a connecting switch for extending the circuit of said line and an operator's telephone set, of a sequence switch having three positions—normal, listening and off-listening—means actuated upon the closure of said connecting switch for moving said sequence switch from said normal to said listening position in which said telephone set is connected in the circuit of said line, other telephone lines and connecting switches, and means actuated upon the subsequent closure of any of said other connecting switches for moving said sequence switch from said listening to said off-listening position in which said telephone set is disconnected from the circuit of said line.

14. In a telephone exchange system, the combination with a calling telephone line, an answering switch for extending the circuit of said line, an operator's telephone set, and a sequence switch, of a relay adapted upon the closure of said connecting switch to cause said sequence switch to connect said telephone set in the circuit of said line, another calling telephone line, answering switch, and sequence switch, and a relay adapted upon the closure of said last mentioned switch to cause said last named sequence switch to disconnect said telephone set from the circuit of the first mentioned line.

15. In a telephone exchange system, the combination with a telephone line, a con-

nnecting switch for extending the circuit of said line, and an operator's telephone set, of a sequence switch, a relay actuated upon the closure of said connecting switch to cause said sequence switch to move into listening position in which said telephone set is connected in the circuit of said line, another telephone line and connecting switch, and a relay actuated upon the closure of said last mentioned connecting switch to cause said sequence switch to move to an off-listening position in which the telephone set is disconnected from the circuit of the first mentioned line.

16. In a telephone exchange system, the combination with a telephone line, a connecting switch for extending the circuit of said line, and an operator's telephone set, of a sequence switch for controlling the connection of said set in the circuit of said line, means actuated upon the closure of said connecting switch for causing said sequence switch to connect said set in said circuit, another telephone line, connecting switch and sequence switch, and means actuated upon the closure of the last mentioned connecting switch for causing the first mentioned sequence switch to disconnect said telephone set from the circuit of the first mentioned line and for causing the last mentioned sequence switch to connect said telephone set into circuit with the last mentioned telephone line.

17. In a telephone exchange system, the combination with a plurality of connecting circuits and an operator's telephone set, of a relay and a sequence switch for each of said connecting circuits, said relay being adapted in the act of extending the associated connecting circuit to a telephone line to cause said sequence switch to connect the telephone set with said connecting circuit, the said sequence switch being adapted in its movement to cause the operation of other sequence switches to disconnect said telephone set from other connecting circuits.

18. In a telephone exchange system, the combination with a plurality of connecting circuits and an operator's telephone set, of a sequence switch associated with each of said connecting circuits, and an electro-responsive device associated with each of said sequence switches and adapted in the act of extending the associated connecting circuit to a telephone line to cause said sequence switch to connect the telephone set in the circuit of said line, and said sequence switch having an element adapted in its movement to cause other sequence switches to disconnect said telephone set from the circuits of other lines.

19. In a telephone exchange system, the combination with a plurality of connecting circuits, switches for extending the circuits of telephone lines, and an operator's tele-

- phone set, of a plurality of relays one for each connecting circuit, a plurality of sequence switches one for each connecting circuit, a local circuit for each of said relays 5 adapted to be closed in the act of extending the circuit of a telephone line, said relay being adapted in its response upon the closure of said local circuit, to cause the corresponding sequence switch to connect said telephone set in circuit with one of said telephone lines and at the same time to place said sequence switch under the control of the other of said sequence switches and said sequence switch having an element adapted 10 in the operation of connecting said telephone set in circuit to cause other sequence switches to disconnect said telephone set from the circuits of other telephone lines.
20. In a telephone exchange system, the combination with connecting circuits, switches for extending said circuits to telephone lines, and an operator's telephone set, of a sequence switch for controlling the connection of said telephone set with each of 25 said connecting circuits, a relay in a local circuit controlled by the switch of each connecting circuit and adapted to control the operation of said sequence switch, said sequence switch having an element adapted in 30 its operation to place it under the temporary control of other sequence switches associated with other connecting circuits, whereby the closing of one of said connecting switches will cause the connection of said 35 telephone set with one telephone line and the disconnection of said set from another line.
21. In a telephone exchange system the combination with a subscriber's line, a connecting circuit therefor terminating in a selector switch, a line switch for extending the circuit of said line to said connecting circuit and sending apparatus for controlling the advance movement of said selector 45 switch, of a listening switch actuated upon the closing of said line switch to connect the operator's telephone in circuit, mechanism for controlling the return movement of said selector switch, and a key adapted only 50 when said operator's telephone is in circuit to control the operation of said mechanism.
22. In a telephone exchange system, the combination with a subscriber's line, a connecting circuit therefor terminating in a selector switch, a line switch for extending the circuit of said line to said connecting circuit, sending apparatus for controlling the advance movement of said selector switch, mechanism for controlling the return movement of said selector switch, and a self-locking relay for controlling the operation 55 of said mechanism, said relay being in a local circuit adapted to be closed upon the opening of said line switch.
23. In a telephone exchange system, the combination with a subscriber's line, a connecting circuit therefor terminating in a selector switch, a line switch for extending the circuit of said line to said connecting circuit, extending apparatus for controlling 60 the advance movement of said selector switch, a listening switch associated with said connecting circuit, a self-locking relay for controlling the return movement of said selector switch, a key adapted in the listening position of said listening switch to control the energization of said relay, and a switch adapted in an off-listening position of said listening key also to control the energization of said relay. 65
24. In a telephone exchange system, the combination with a subscriber's line, a connecting circuit therefor terminating in a selector switch, a line switch for extending the circuit of said line to said connecting circuit, and sending apparatus for controlling the advance movement of said selector switch, of a listening switch, a self-locking relay for controlling the return movement of said selector switch, a cord relay, and a 70 wipe-out key, said cord relay being under the control of said line switch and said locking relay being under the control of said wipe-out key when the listening switch is in listening position and under the control of 75 said cord relay when the listening switch is in off-listening position.
25. In a telephone exchange system, the combination with a subscriber's line, a connecting circuit therefor terminating in a selector switch, a line switch for extending the circuit of said line to said connecting circuit, and sending apparatus for controlling the advance movement of said selector switch, of a listening switch, a restoring relay for controlling the return movement of 80 said selector switch, a cord relay, and a wipe-out key, said cord relay being under the control of said line switch, and said listening switch having an element adapted in 85 its movement to an off-listening position to shift the control of said restoring relay from said wipe-out key to said cord relay. 90
26. In an automatic telephone exchange system, the combination with selector mechanism and sender mechanism for controlling the operation of said selector mechanism to interconnect subscribers' lines, of a supervisory signal, a relay responsive to current in a called line when connection is made 95 thereto, and a sequence switch adapted in one position to cause the operation of said supervisory signal, and means under the control of the sender mechanism to advance said sequence switch to a position in which 100 said supervisory signal is under the control of said relay. 105
27. In an automatic telephone exchange system, the combination with selector mechanism and sender mechanism for controlling 110

- the operation thereof to interconnect subscribers' lines, of a supervisory signal, a ringing signal, a relay responsive to current in a called line when connection is made thereto, and a sequence switch adapted in one position to close the circuit of said supervisory signal, means under the control of said sender mechanism to advance said sequence switch to a position in which said ringing signal is under the control of said relay, and means under the control of said relay to advance said sequence switch to another position in which said supervisory signal is under the control of said relay.
28. In an automatic telephone exchange system, the combination with selector mechanism and sender mechanism for controlling the operation thereof to interconnect subscribers' lines, of a supervisory signal, a ringing signal, a relay responsive to current in a called line when connection is made thereto, a sequence switch adapted in one position to connect said sender mechanism to said selector mechanism, means under the control of said sender mechanism to advance said sequence switch to a position in which the circuit of said ringing signal is closed to a contact of said relay, and means under the control of said relay to advance said sequence switch to another position in which the circuit of said supervisory signal is closed to said contact of said relay.
29. In a telephone exchange system, the combination with a calling line, a connecting circuit therefor and a supervisory signal adapted when connection is made with the calling line to respond to flow of current therein, of automatic switching mechanism for extending the circuit of said calling line through said connecting circuit to another line, and means controlled by said switch-
- ing mechanism for maintaining the operation of said supervisory signal when the connection with the calling line is broken.
30. In a telephone exchange system, the combination with a calling line, a connecting circuit therefor and a supervisory signal adapted when connection is made with the calling line to respond to flow of current therein, of automatic switching mechanism for extending the circuit of said calling line through said connecting circuit to another line, and a relay under the control of said switching mechanism adapted to maintain a circuit for said supervisory signal when connection with the calling line is broken and until said switching mechanism is restored to normal.
31. In a telephone exchange system, the combination with a calling line, a connecting circuit therefor, a line relay responsive to current in the calling line when connection is made thereto, and a cord relay in a local circuit closed when connection is made with said calling line, of a supervisory signal in a local circuit controlled jointly by said line and cord relays, switching mechanism for extending the circuit of said calling line through said connecting circuit to another line, and a switch controlled by said switching mechanism and arranged to maintain the local circuit of said supervisory signal closed when connection is broken with the calling line and until connection is broken with said other line and said switching mechanism is restored to normal condition.
- In witness whereof, I hereunto subscribe my name this 25th day of July, A. D., 1910.
- FRANK R. McBERTY.
